UNITED STATES PATENT OFFICE.

ALBERT S. KOROB, OF CHICAGO, ILLINOIS.

GRIPPER FOR PRINTING-PRESSES.

1,353,808.

Specification of Letters Patent. Patented Sept. 21, 1920.

Application filed April 4, 1919. Serial No. 287,435.

To all whom it may concern:

Be it known that I, ALBERT S. KOROB, a citizen of Russia, and a resident of Chicago, county of Cook, and State of Illinois, have 5 invented certain new and useful Improvements in Grippers for Printing-Presses, of which the following is a specification.

My invention relates to grippers for printing presses, and has for its object improvements in such devices. I have illustrated my invention as applied to an ordinary Gordon press, and in the accompanying drawings I have shown so much of such 10 press as is necessary to an understanding of 15 the invention.

In the said drawings—

Figure 1 is an elevation of the device shown resting against the face of the movable platen of a Gordon press; 20 Fig. 2 is an enlarged detail of one corner of the device, viewed in a direction opposite to Fig. 1;

Figs. 3, 4 and 5 are enlarged sections on lines 3—3, 4—4, and 5—5, respectively, of 25 Fig. 1;

Fig. 6 is a view in the direction 6—6 of Fig. 5; and

Fig. 7 is a section on line 7—7 of Fig. 1, but with the gage block moved to position 30 under the gripper.

In the said drawings, A is the platen of a Gordon press, and B is a bar which is pivoted to the platen by connections not shown because they form no part of the present invention. The bar B has therein a slot C by 35 means of which the ordinary grippers are adjusted to any position on the face of the platen A by shifting the bolts D along the slot C. So far the parts are the same as they 40 are in the ordinary press. What I do is to remove the ordinary grippers and substitute therefor the grippers 10 and 11 with their connected parts to be hereinafter described. The new grippers are held in place by the 45 same bolts D, so these parts need no further description.

The grippers 10 and 11 are made of angle irons which are so placed as to have the 50 short legs of the angles projecting toward the platen A, and located on the edges farthest from the central part of the platen. This relationship may be seen in Figs. 4 and 5. One object of this is to provide a vacant 55 space so as to make it possible for the gage blocks E to be located beneath the grippers. The blocks E are small blocks which the

printer secures on the platen A and by which he locates the sheets of paper in feeding the press by hand. The ordinary grippers are solid rectangular bars, and as these 60 bars must come against the face of the platen, gage blocks such as E must come between the grippers. By making my grippers 10 and 11 of angle iron placed as shown, I can let the gage blocks come under 65 the gripper, as shown in Fig. 7. By this means I am enabled to print a wider sheet than is possible when plain rectangular grippers are used.

In each of the grippers 10 and 11 I provide slots 12, and through these slots run screws 13 which connect blocks 14 and 15 on opposite sides of the long leg of the angle which forms the grippers. The block 14 has a tongue which fits in the slot of the gripper 70 as shown in Fig. 4, and the block 15 has grooves 16 and 17 as shown in Fig. 5. The groove 16 is designed to receive a wire 18, and the groove 17 is designed to receive a flat spring 19. These blocks 14 and 15 with 75 screw 13 are intended to hold either a wire or a spring, as may be most appropriate or convenient, at any desired position on the length of the gripper. The supported wire or spring will be called a "finger" for convenience, and these fingers are intended to project inward over the paper being printed upon and to remove the paper from the type when the platen falls back after making an impression. In any type form of considerable 80 size, there are blank spaces of some size between the lines of type, or spaces at the ends of short lines of printing. By means of the slots 12, screws 13 and holding blocks 14 and 15, the fingers (either wire or 85 spring) may be adjusted to match these vacant spaces. The fingers are loose pieces which may be of any length, and which are clamped in position when the screws 13 are tightened. The number of fingers for each 90 gripper 10 or 11 may be anything desired. It is to be observed that the clamping blocks 15 come in the vacant spaces under the grippers, and that it is in these same spaces that the gage blocks E may be placed when 95 printing on wide sheets of paper.

I also provide a cross bar 20 which is also of angle iron and has a slot 21. The ends of the bar 20 have secured thereto pieces 22 which are secured to the grippers 10 and 11 100 by screws 23 and blocks 24. The screws 23 and blocks 24 are identical with screws 13

and blocks 14, and serve as means by which the bar 20 is vertically adjustable on the grippers 10 and 11. Clamping blocks for fingers are adjustable along the slot 21 as 5 previously described for the slots 12. The bar 20 is used only when it is desired to print large sheets of paper. For smaller sheets, the bar 20 is removed and the grippers 10 and 11 are adjusted to desired positions along the slot C by means of the 10 screws D.

What I claim is:

1. The combination with a gripper having a longitudinal slot therein, of blocks located on opposite sides of the gripper and 15 clamped to the gripper by a screw passing through said slot, one of said blocks having

a groove in its face perpendicular to the line of the slot in the gripper, and a finger secured in said groove by the clamping action of said screw. 20

2. The combination with a gripper having a longitudinal slot therein, of blocks located on opposite sides of the gripper, a screw extending through said slot and serving to clamp the blocks to the gripper, one of said blocks having a plurality of transverse grooves in the face adjacent to the gripper, said grooves being of different dimensions to accommodate fingers of different shapes, and fingers designed to fit said grooves and be clamped to said grippers by 25 30 said screw.

ALBERT S. KOROB.
